UNITED STATES PATENT OFFICE.

CHARLES ANDRE DUKE, OF NEW YORK, N. Y.

KNOCKDOWN STAND.

Application filed June 11, 1926. Serial No. 115,300.

The present invention relates to knock-down portable stands, such as are used to furnish seats for viewing parades, circus performances, athletic games, etc., and the invention aims to provide a stand of that kind comprising a novel assemblage of the component elements to provide a substantial stand, when erected, which may be conveniently taken apart for shipment or storage within small space.

Another object is the provision of stringers having novel means thereon for supporting and holding wooden boards to provide seats and foot rests.

A further object is the provision of novel clips for holding the seat and foot boards in place without using bolts, screws or other securing elements, and without drilling holes or cutting notches in the boards.

A still further object of the invention is the provision of novel means for mounting inclined stringers upon supporting members to provide a rigid structure which is not apt to tilt or collapse accidentally.

The invention has for another object the construction of a stand of the kind indicated which, with the exception of the seat and foot boards, may be constructed of metal.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a perspective view of the improved stand, showing one seat board and one foot board in dotted lines.

Fig. 2 is a detail view in perspective showing one of the connections between the stringers and supports.

Fig. 3 is a perspective view of one of the foot board holding clips.

Fig. 4 is a perspective view of one of the seat board holding clips.

One stand unit is shown in Fig. 1, and it will be understood that any number of units may be assembled, and that each unit may be of a different size.

Each unit comprises the front and rear supports 5 and 6, respectively, comprising frames constructed of angle iron or other suitable stock, and adapted to seat on the

ground, pavement or other surface in upright position for supporting the inclined stringers 7, that extend over said supports. The rear support 6 is of greater height than the front support 5, and any number of supports may be used according to the length of the stringers. The stringers 7, as shown, are of channel iron, and the unit has two stringers, but may have more.

The stringers are detachably secured on the supports, to enable them to be separated. Thus, the supports have at their opposite sides the outstanding portions or flanges 8, which may be flanges of angle iron pieces secured to the supports, and said portions 8 are disposed substantially flush with the upper portions of the supports and are horizontal. Angle iron pieces 9 are riveted, welded, or otherwise secured to the stringers 7 and have the lower outstanding flanges or portions 10 disposed horizontally and adapted to bear snugly on the portions 8. Bolts 11 or other removable securing elements extend through registering apertures in the portions 8 and 10 for clamping them together, thereby holding the stringers and supports assembled. The portions 8 and 10 being in horizontal planes will result in the stringers being supported by the supports in a substantial manner, and the weight is transmitted slightly downward from the stringers to the supports, without tendency for the supports to be tilted forwardly or rearwardly, notwithstanding the fact that the stringers are inclined. By removing the bolts 11 the stringers and supports are readily separated for shipment or storage within small space.

Upwardly extending brackets or standards 12, of angle iron stock as shown, are riveted, welded, or otherwise secured to the stringers 7 at longitudinally spaced intervals along said stringers, and have their upper terminals formed into or provided with portions 13 on which seat boards 14 are supported. The boards 14 provide seats above the stringers one behind the other at increasing heights.

A clip 15 is assembled with each bracket 12 or standard 12 for holding the seat board thereon. Each clip 15 is constructed from two bars. One bar has a portion 16 to extend transversely across the seat board, with a depending terminal 17 at the forward end of the portion 16 to overlap the forward edge of the seat board. The bar has a de-

2

pending portion 18 at the rear end of the portion 16 to extend across the rear edge of the seat board, with a portion 19 extending forwardly and downwardly from the portion 18, and a downwardly extending terminal portion 20 extending from the portion 19. The other bar 21 is of U-shape to fit astride the bracket or standard 12 from one side, preferably the inner side. The rear arm of the bar 21 and portion 20 of the other bar are welded or otherwise secured together. The clips 15 are made in rights and lefts for use at the opposite sides of the unit, as seen in Fig. 1, and by placing the portion 16 over the seat board 14, with the portions 17 and 18 engaging the front and rear edges of the seat board, the clip may be slid on the board to move the bar 21 astride the bracket or standard 12, under the portion 13, thereby holding the seat board firmly in place on the standard. The clips 15 may be assembled with the standards 12 and the boards 14 slid lengthwise over the portions 19 and under the portions 16, when assembling the structure.

Cleats 22, which are of angle iron stock as shown, are welded, riveted or otherwise secured to the stringers 7 in front of the standards 12 and are substantially horizontal to support thereon the foot boards 23. The rear terminals of said cleats are secured to the stringers and their forward terminals project forwardly above the stringers.

Clips 24 are employed for holding the foot boards 23 on the cleats 22, and each clip 24 is composed of two bars. One bar has a forwardly extending terminal portion 25 to overlap the upper surface of the board 23, with a portion 26 to extend across the rear edge of the board, and a portion 27 projecting forwardly to overlap the lower surface of the board. The opposite terminal of the bar is offset downwardly, as at 28, at the forward end of the portion 27, and is welded or otherwise secured on the upper angularly extending terminal 29 of a bar 30 which has the hook 31 at its lower end. The bar 30 extends across the stringer 7, preferably at the inner side thereof as shown, with

the hook 31 engaging under the lower edge 50 of the stringer, and the hook portion of the upper bar comprising the portions 25, 26 and 27 fits astride the rear edge portion of the board 23, thereby holding the board down in place on the adjacent cleat 22. The clips 55 24 are readily applied after the boards 23 are in place, or the clips may be applied first to the stringers and the foot boards slid lengthwise across the cleats 22 and into the clips 24.

Having thus described the invention, what is claimed as new is:—

1. A knock-down stand comprising supports of different heights having upper horizontal portions, and inclined stringers extending over said supports and having provisions for supporting boards thereon and having horizontal portions to bear on said horizontal portions of the supports.

2. A knock-down stand comprising supports of different heights having upper outstanding horizontal portions, and inclined stringers extending over said supports and having provisions for supporting boards thereon and having outstanding horizontal 75 portions, detachably secured on the aforesaid horizontal portions of said supports.

3. A knock-down stand comprising stringers, a board extending across and seated on said stringers, and clips having portions to be slipped into engagement with one edge portion of the board and to fit astride said edge portion, and the clips having lower hooks to engage under the stringers.

4. A knock-down stand comprising inclined stringers having substantially horizontal board-supporting portions thereon, said stringers having inclined lower edges, a board extending across and seated on said portions, and clips having upper portions formed to slip into engagement and fit astride the rear edge portion of the board and having lower hooks to engage under the lower edges of the stringers.

In testimony whereof I hereunto affix my signature.

CHARLES ANDRE DUKE.
